(57) **CLAIM**

I claim the new and original design for a surface mounted electrical cable way, as shown and described.

DESCRIPTION

FIG. 1 is a perspective view, showing my new design and illustrating the cable way of the present invention as it would appear mounted to a wall surface, the phantom line portions forming no part of the design.

FIG. 2 is a rear quartering perspective view of the cable way illustrated in FIG. 1, the phantom line portions forming no part of the present invention; and,

FIG. 3 is a side elevation view of the cable way illustrated in FIGS. 1 and 2.

1 Claim, 3 Drawing Sheets

FIG. 2

FIG. 3
